(57) **CLAIM**

The ornamental design for a buoy, as shown and described.

DESCRIPTION

FIG. 1 is a top plan view of a first embodiment of a buoy showing my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom plan view thereof;

FIG. 7 is a top plan view of a second embodiment of the buoy;

FIG. 8 is a front elevational view thereof;

FIG. 9 is a left side elevational view thereof;

FIG. 10 is a rear elevational view thereof;

FIG. 11 is a right side elevational view thereof; and,

FIG. 12 is a bottom plan view thereof.

The broken lines shown in the drawings illustrate environmental structure and form no part of the claimed design.
